RECEPTACLE

Frank C. Woelfer, Jr., Cincinnati, Ohio, assignor
to The Cincinnati Ball Crank Company, Cincinnati, Ohio, a corporation of Ohio

Application July 18, 1936, Serial No. 91,349

5 Claims. (Cl. 221—11)

This invention relates to receptacles, and is particularly directed to a pail or bucket of the character used for filling radiators in service stations.

5 The equipment for modern service stations must be symmetrical and graceful. This requirement extends to all the equipment used in servicing an automobile. The old fashioned water can or bucket for filling radiators is ungainly, since it 10 is of irregular outline and awkward shape, and presents unsightly projections.

It is the object of the present invention to provide a water bucket or pail which is so fabricated as to provide a well rounded shape and neat 15 appearance without loss of serviceability. For this purpose, parts of an entirely new and improved form are provided, and are assembled in a highly novel manner. The present invention is not directed to the ornamental appearance but 20 pertains to the structural arrangement, making possible an ornamental appearance.

It is also the fact that equipment of this character, that is, metal receptacles, receives a great deal of hard usage and careless treatment in service. Accordingly, it must be quite durable and must be fabricated and assembled in a manner precluding breakage at the joints such as would cause leakage. It is, accordingly, another object 25 of this invention to provide an improved water 30 pail or bucket which is formed of relatively few parts, which parts are joined in a manner resisting breakage at the joints and lending greater rigidity to the bucket. Additionally, the fabrication is such as to enable production of the buckets at very low cost. This saving not only extends to the initial formation of the parts but to 35 the assembly operations as well.

It is a further object of this invention to provide a radiator filling receptacle which is of an 40 improved form for greater convenience in carrying and using the same.

Other objects and certain advantages will be more fully apparent from a description of the accompanying drawing, in which:

45 Figure 1 is a side elevation of the improved receptacle, a portion of the base element thereof being broken away for the purpose of illustrating its arrangement relative to the body of the can.

Figure 2 is a rear view of the improved bucket.

50 Figure 3 is a top plan view thereof, a portion of the spout being broken away for illustrating the connection of an extension thereto.

Figure 4 is a sectional view taken on line 4—4, Fig. 1.

55 Figure 5 is a fragmentary sectional view taken

on line 5—5, Fig. 1, detailing the connection to the main part of the body of the support or base element thereof.

The present concept results from the determination that the water buckets of the past were 5 too cumbersome and awkward, and these faults made it difficult to handle the buckets in the operation of servicing the car. The invention, one embodiment of which is herein disclosed, resides in the provision of a bucket formed of 10 pressed steel parts to provide a gracefully shaped receptacle and one which is easily assembled, water-tight, and durable. To this end, pressed steel halves are joined along a central vertical line. These halves include in each case a portion of the spout and body of the receptacle, and thus eliminate the necessity for a separate spout element and add to the grace of the product. Furthermore, supplemental metal parts provide 15 an improved base for the receptacle, and means 20 for pouring therefrom as well as means for handling the receptacle for the operation of pouring.

Referring to the drawing, the pressed steel 25 halves or shells, indicated at 10, are duplicates. Each half includes a portion 11 forming half of the body and a portion 12 forming half of the spout. Marginal flanges 13 extend continuously around the edges of the shells with the exception of the spout opening. These flanges abut, with the exception of the filling opening, when the 30 shells are placed together for forming the vertical central joint heretofore discussed. Appropriate means is employed for fastening the parts thus 35 formed together, the most adequate means being welding.

The body portions, when viewed in horizontal section, form an oval-shaped receptacle. The upper portions thereof are formed to provide the inlet opening 14 through which the water is delivered to the receptacle. The metal shells are 40 well rounded at all corners, and, as viewed in side elevation, the substantially continuous attaching flanges are fully curved to eliminate sharp corners or objectionable obstructions.

In order to provide a solid base for the receptacle, a band 15 encircles the lower portion thereof. The band is in sections 16, 16, which lie in an annular groove 17, pressed into the lower parts of the shells. The base elements 16, 16, project below the bottom of the shell elements to provide 50 a false bottom. The band is in sections so as to clear the flanges 13 of the shell, the ends of the sections lying against the flanges.

A main carrying handle element 18 straddles the upper part of the finished can and is spot- 55

welded thereto. The handle is of U-shape for this purpose. A tipping handle 19, also of U-shape, straddles the rear lower portion of the receptacle and is spot-welded thereto.

5 A tubular extension 20, of arcuate form as to its length, is secured between the shells at the outer open end of the spout portions thereof, being welded in this position. This spout extension 20 provides for easy delivery of the water 10 to the radiator since the tube fits within the radiator filling opening without difficulty, and is sufficiently curved for the purpose of ease in entering the filling opening.

It will be apparent that the improved bucket 15 herein disclosed in one form may be used for any purpose having general utility apart from the specifically described use.

Having described my invention, I claim:

1. A receptacle of the class described, comprising, metal shells, each of which constitutes half 20 of the receptacle and the spout therefor, said parts united on a vertical central line and providing a receptacle which is oval in horizontal plane, and having an integral spout extending 25 forwardly and upwardly therefrom, a base member in the form of a band secured around the bottom of the abutted and joined parts for supporting the receptacle body clear of a supporting surface, and handle means for carrying and tipping said receptacle in pouring.

2. A receptacle formed of a pair of stamped metal shells forming halves of the receptacle body and spout, and including substantially continuous marginal flanges lying in abutment and weld-

ed together to form a vertical central seam, a band forming a base for the receptacle, encircling the base of the shells and secured within an annular depression thereof, a spout extension having one end secured within the spout portion 5 of the shells, and handles for the receptacle secured at the top and rear thereof.

3. A radiator filling bucket formed of sheet metal and consisting of pressed steel shells abutted and joined on a vertical line said shells 10 forming the bottom of the bucket, the bottom portions being joined on the same vertical line as the side portions, and a support band encircling the base of the assembled shells.

4. A receptacle of the class described, comprising, stamped metal shells, each of which includes a flange around its edge and constitutes half of the receptacle and the spout therefor, said flanges extended outwardly in parallelism for flush abutment, said parts when the flanges are united in a 20 vertical central plane providing a receptacle which is oval in horizontal plane, and having an integral spout extending forwardly and upwardly therefrom, and a base member for supporting the receptacle body clear of the supporting surface. 25

5. A receptacle of the class described, comprising, metal shells, each of which constitutes half of the receptacle and the spout therefor, a base member in the form of a band secured around the bottom of the abutted and joined parts for 30 supporting the receptacle body clear of a supporting surface, and handle means for carrying and tipping said receptacle in pouring.
